UNITED STATES PATENT OFFICE.

GEORGE E. ROLLINS, OF BROCKTON, MASSACHUSETTS, ASSIGNOR TO ABRAM SYDEMAN,
OF BOSTON, MASSACHUSETTS.

HEEL PROTECTOR OR SLUG.

1,285,797.

Specification of Letters Patent. Patented Nov. 26, 1918.

Application filed January 8, 1914. Serial No. 810,941.

To all whom it may concern:

Be it known that I, GEORGE E. ROLLINS, a citizen of the United States, and a resident of Brockton, county of Plymouth, and State 5 of Massachusetts, have invented an Improvement in Heel Protectors or Slugs, of which the following description, in connection with the accompanying drawings, is a specification, like characters on the drawings representing like parts.

This invention relates to heel protectors, or slugs, intended to be driven into the tread surface of a heel to prevent rapid wearing away of the leather, rubber, canvas or 15 other material of which the heel is made. My invention will be best understood by reference to the following specification, when taken in connection with the accompanying drawing, showing one illustrative 20 embodiment thereof, while its scope will be more particularly pointed out in the appended claims.

In the drawings:

Figure 1 is a perspective view on an enlarged scale of a heel protector, or slug, embodying my invention;

Fig. 2 is a sectional view of the protector, or slug driven through the top-lift of a heel;

Fig. 3 is a sectional view of the protector and top-lift, showing one set of spurs clenched;

Fig. 4 is a sectional view of the protector and a portion of the heel, after the top-lift 35 has been attached;

Fig. 5 is a bottom plan of the heel having a plurality of the protectors embedded therein;

Fig. 6 is a bottom plan of another heel 40 having a plurality of the protectors embedded therein; and

Fig. 7 is a sectional view on line 7—7 of Fig. 6.

Referring to the drawings, and to the embodiment of my invention which I have there shown for illustrative purposes, 6 is a base, preferably provided with an aperture 7. The base may have one or more flanges, preferably two designated by the 45 numerals 8 and 9, projecting from one face thereof, and either or both of these flanges may be provided with one or more prongs. In the specific device selected for illustration, the inner flange 8 is provided with a

plurality of prongs 10, herein four in number, while the outer flange 9 is similarly provided with a plurality of prongs 11, herein four in number. The prongs are preferably V-shaped in form, and are preferably provided with sharp points, as shown. It will 55 be understood, however, that the prongs may be widely varied as to their number and form, within the scope of my invention. If desired, the prongs 11, or any other part of the structure, may be provided with suitable lateral spurs, as exemplified by the spurs 12 on the prongs 11. Such spurs will materially assist in retaining the protector in the leather, and prevent its accidental withdrawal therefrom.

While the base 6 may be of any other suitable form having a closed perimeter, it is herein annular, and the projecting flanges are also annular. Preferably, the sides of the flanges and their prongs diverge from 70 the base, and where the flanges are annular, as in the present instance, the surfaces of the flanges are of generally frusto-conical form. The prongs may be otherwise proportioned as to their relative lengths, but 75 herein the inner prongs 10 are relatively shorter than the outer prongs 11.

While the protector may be made of any other suitable material, and shaped into the described form in any other suitable manner, the specific protector is made of sheet metal, as for example sheet steel, stamped or pressed into the desired form. If desired, the protector may be simply driven into the finished heel, but I prefer to drive it 80 through the top-lift 13, as shown in Fig. 2, and afterward attach the top-lift to the body 14 of the heel. In driving the protector into the top-lift, the prongs cut their way into the leather, and prepare the latter 85 for the entrance of the flanges, it having been found in practice that the latter will readily enter the leather, and the protector will sink into the leather flush therewith.

Owing to the tapered form of the internal surfaces of the protector, the leather inclosed thereby becomes highly compressed, and rendered so dense as to materially assist in holding the protector, as well as to present within the aperture 7 a wearing surface 100 of great durability. After the protector has been driven into the top-lift, the prongs 10 are preferably clenched, as shown in Fig. 105

3, by means of a suitable tool. The top-lift is then attached to the heel body, by driving the spurs 11 thereinto. Usual heel nails 15 project above the surface of the heel body, 5 entering the top-lift as seen in Fig. 4, and aid in securing the top-lift to the body.

One or more of the heel protectors may be embedded in a heel in any desired position, or positions, according to the tendency to 10 wear the heel at one point more than at another. In Fig. 5, I have shown, for purposes of exemplification, a large protector in the heel at the rear portion, and two smaller ones adjacent the forward corners 15 of the heel. Each protector, when embedded in the heel, not only prevents rapid wearing away of the leather, rubber, canvas or other material, but also tends to prevent slipping of the heel upon the pavement.

20 In Figs. 6 and 7, I have shown the protector as applied to a rubber heel, and in this case, although the protector itself is not essentially changed, its mode of application to the heel is somewhat different from 25 its application to leather heels. The protector is first driven through one or more thicknesses of canvas, or other suitable fabric, 16 cemented or otherwise appropriately fastened together, and the portion of the 30 fabric encircled by the protector is preferably pressed outward beyond the face of the protector, to present a yielding, non-slipping tread surface. If desired, the 35 layers of canvas or other fabric may be stitched together within the circle of the protector, by one or more suitably arranged rows of stitches 17. These stitches will serve to firmly unite the several layers of fabric, and hold them together as they gradually 40 wear away.

After the protector has been driven through the layer or layers of fabric, the inner set of prongs 10 may be, and preferably are, then bent laterally, as shown in 45 Fig. 7. The protector and layer or layers of fabric, when thus united, are next placed in a suitable mold, and rubber, or other appropriate composition, is then molded around and about the protector and fabric, 50 thus embedding both, except that the face of the protector and the portion of the fabric which it encircles are exposed and substantially flush with the tread surface of the heel, although as before stated, the portion 55 of the fabric which is encircled by the protector preferably extends somewhat beyond the general tread surface of the heel, as shown in Fig. 7. This provides a means for preventing the rapid wearing away of 60 the rear edge of the rubber heel, while at the same time forming a means effectually to prevent the heel from slipping on the pavement. Moreover, the mode of fastening the protector in the rubber heel is such 65 that it is impossible to pull the protector

out without practically destroying the heel. Preferably, the prongs 9 extend through the upper face of the rubber heel far enough to be driven into the leather heel of the shoe, in applying the rubber heel thereto. 70

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts nor to its specific embodiment herein shown, but that extensive deviations from the illustrated form or embodiment of the invention may be made without departing from the principles thereof. 75 80

Having thus described my invention, what I claim and desire by Letters Patent to 85 secure is:—

1. In combination, a foot wear tread having an exterior layer and a protector therefor including a base having prongs clenched in said exterior layer and other prongs penetrating said layer and entering the body of the tread therebeneath. 90

2. A protector comprising a base and a pair of flanges thereon forming between them a channel and penetrative members 95 aligning with and forming continuations of said flanges whereby said protector may be driven into a tread up to said base.

3. In combination, a foot wear tread having an outer surface of resilient material, a fibrous member having a portion presented at the wearing surface and a member engaging the lateral portions of said fibrous member and including a frame-like body having provision for fastening the same extending laterally in engagement with the tread. 100 105

4. In combination, a foot wear tread having an outer surface of resilient material, a fibrous member having a portion presented at the wearing surface and a member including a frame-like body engaging the lateral portions of said fibrous member and having prongs clenched thereon and other prongs extending into said tread. 110

5. In combination, a foot wear tread having an outer surface of resilient material, a fibrous member having a portion presented at the wearing surface and a member engaging the lateral portions of said fibrous member and including a frame-like body having provision for fastening the same extending laterally in engagement with the tread, said fibrous member having fibers therein bridging across said frame and held by opposite parts thereof. 120 125

6. In combination, a foot wear tread having an outer surface of resilient material, a fibrous member having a portion presented to the wearing surface and a frame-like 130

- member engaging the lateral portions of the fibrous member, said fibrous member having fibers therein bridging said frame, said frame including a plane portion disposed substantially parallel to the wearing surface and prongs extending therefrom into the tread. 5
7. In combination, a foot wear tread having an outer surface of resilient material, a fibrous member having a portion presented 10 at the wearing surface and a member engaging the lateral portions of said fibrous member and including a frame-like body presenting an outwardly flaring wall for engagement with the tread.
- 15 8. In combination, a foot wear tread having an outer surface of resilient material, a fibrous member having a portion presented to the wearing surface and a retaining member for said fibrous member engaging the 20 same along lines oblique to the tread surface whereby to retain the same against withdrawal and penetrative fastening means for said retaining member entering the body of the tread.
- 25 9. In combination, a resilient foot-wear tread member having a tread surface, a wear-resisting member embedded in said tread member and having a portion presented at the tread surface and another portion 30 contacting with said tread member, and anchor means laterally interlocking with said members.
10. In combination, a resilient foot-wear tread member having a tread surface, a 35 wear-resisting member embedded in said tread member and having a portion presented at the tread surface and another portion contacting with said tread member, and anchor means embracing a portion of said 40 wear-resisting member and laterally interlocking with said members.
11. In combination, a resilient foot-wear tread member having a tread surface, a wear-resisting member embedded in said 45 tread member and having a portion presented at the tread surface and another portion contacting with said tread member, and anchoring means having portions interposed between and directly engaging said tread 50 member and said wear-resisting member and interlocked with both, thereby to lock said wear-resisting member to said anchoring
- means and to lock said anchoring means to said tread member.
12. In combination, a resilient foot-wear tread member having a tread surface, a wear-resisting member embedded in said tread member and having a portion presented at the tread surface and another portion contacting with said tread member, and an annular member inclosing a portion of said wear-resisting member and having portions interlocking with said tread member and said wear-resisting member. 55
13. In combination, a resilient foot-wear tread member having a tread surface, a wear-resisting member having a portion presented at the tread surface, and an anchor member inclosing a portion of said wear-resisting member and provided with one or 60 more openings into which a portion or portions of said tread member extend into contact with said wear-resisting member. 65
14. In combination, a resilient foot-wear tread member having a tread surface, a wear-resisting member having a portion presented at the tread surface, and an anchor member inclosing a portion of said wear-resisting member and notched to receive a portion or portions of said tread member. 70 75
15. In combination, a resilient foot-wear tread member having a tread surface, a wear-resisting member having a portion presented at the tread surface, and an annular member inclosing a portion of said wear-resisting member and provided with one or 80 more openings into which a portion of portions of said tread member extend. 85
16. In combination, a resilient foot-wear tread member having a tread surface, a wear-resisting member having a portion presented at the tread surface, and anchor means having portions interlocked with one of said members and having a spur extending into said tread member to assist in holding said wear-resisting member in said tread member. 90 95

In testimony whereof, I have signed my name to this specification, in the presence of two subscribing witnesses.

GEORGE E. ROLLINS.
